(57) **CLAIM**

The ornamental design for a cycle slip, as shown and described.

DESCRIPTION

Inventor has recently filed a previous design patent application as a co-inventor to which this one may or may not be related. Please reference application Ser. No. 29,658,699. FIG. 1 is a front view of a cycle slip, showing our new design;

FIG. 2 is a left side view thereof; and,

FIG. 3 is a top, right perspective view thereof.

In the drawings, the broken lines depict portions of a bicycle that form no part of the claimed design.
